FRENCH-BINDING STRAIGHTENING
MACHINE

Arthur S. Johnson, Beverly, Mass., assignor to
United Shoe Machinery Corporation, Paterson,
N. J., a corporation of New Jersey

Application October 16, 1931, Serial No. 569,295

5 Claims. (Cl. 12—80)

This invention relates to improvements in French-binding machines and the invention is herein illustrated as embodied in a machine for rubbing out or straightening a fabric French-binding strip attached to a marginal portion of a shoe upper preparatory to folding this strip about the margin of the upper. The illustrated machine is a French-binding straightening and cementing machine of the type illustrated in my 10 copending application Serial No. 346,383, filed March 12, 1929.

Where the edges of upper pieces are covered with a fabric binding strip in order to produce the so-called French edge, it is customary to rub out or straighten the fabric strip so that it will extend beyond the edge of the piece of work. Cement is then applied to the straightened strip and to the margin of the upper, and the work is presented to a folding machine which folds 20 the strip around the edge of the upper. In the use of machines of the type illustrated in the above-mentioned application, the steps of straightening and cementing have been combined in a single machine but other machines are provided which are used for straightening alone.

This operation of rubbing out or straightening the fabric strip requires the application of considerable force to the work, and care must be taken when working upon a delicate material to 30 avoid damaging the material by scuffing its surface with the wiper or rubbing-out tool. This is especially necessary at points such as at seams where the thickness of the work is considerably greater than elsewhere and if, in consequence, the feeding of the work is momentarily interrupted this only adds to the difficulty by causing the rubbing-out tool to be applied for more than the usual length of time to a single spot on the work.

An object of the present invention is to provide 40 an improved straightening tool in the use of which there will be no danger of damage to the work.

To this end and in accordance with a feature 45 of the invention, the illustrated rubbing-out or straightening tool has a work-contacting member comprising a helical spring wrapped around the periphery of the tool and resiliently held thereon in such fashion that the convolutions of the spring may slide along the periphery of the tool when an obstruction is encountered. Preferably, and as illustrated, the spring is positioned within a groove formed in the periphery of the 50 tool, and is yieldably held in the groove by means

of a split ring threaded through the convolutions of the spring.

These and other features of the invention will be best understood from the following description taken in connection with the accompanying drawing, in which

Fig. 1 is an enlarged front elevation of the tool;

Fig. 2 is a vertical section on the line II—II of Fig. 1;

Figs. 3 and 4 are views on a still larger scale showing the tool, with portions broken away, as embodied in a straightening and cementing machine and illustrating in Fig. 4 the action of the tool upon an unusually thick portion of the work.

Fig. 5 is a detail view in perspective of a fragment of the tool showing corrugations in the bottom of the grooved periphery; and

Fig. 6 is another detail view illustrating the manner of joining the ends of the helical spring.

The straightening tool or wiper disk 10 is adapted to be mounted upon a driven shaft 12 by means of a bayonet joint 14 in a hub 16, which joint 14 coacts with a transverse pin 18 on the shaft. The body of the disk comprises a web 20 which is comparatively thin and a thickened rim 22 having an outwardly extending flange 24 which is positioned alongside a recess 26. A thin disk or plate 30 applied to the outer face of the tool by means of screws coacts with the recess 26 and the flange 24 to form a U-shaped groove, in which groove there is positioned a helical spring 32 forming the work rubbing member. This spring may be held in the groove by virtue of its own resiliency or a ring 34, which is split at 36 and threaded through the convolutions of the spring, may be provided which will give added pressure to hold the spring in the groove. The ring 34 substantially fills the convolutions of the spring 32, making the construction strong and not easily put out of order, while still permitting circumferential sliding of the coils of the spring. In constructing the tool, it is found desirable to apply solder not only to the meeting ends of the coiled spring 32 but also to extend the mass of 40 solder, as shown at 38 (Fig. 6), to cover the adjacent convolutions of the spring, thereby furnishing additional strength to the construction.

Corrugations 39 are formed in the bottom of the groove, as shown in Fig. 5, which are skewed 50 so that they resemble a screw thread. By reason of this skewed position, they coact better with the convolutions of the spring 32. As will be seen from Fig. 2, the corrugations occupy only the bottom portion of the groove, and the sides of 55

the groove formed by the flange 24 and the plate 30 are smooth, thus giving an opportunity for each individual coil to rock slightly in the groove as it encounters the binding strip 40, as shown in 5 Fig. 3.

The tool is herein illustrated as embodied in a French-binding straightening and cementing machine of the type shown in my copending application to which reference has been made above. 10 The work-piece 42 is supported upon a cement-applying roll 44, and the binding strip 40, which is attached to the work-piece 42 by a row of stitches 46, is vigorously straightened and caused to extend outwardly from the work-piece by the action 15 of the tool 10. In this type of machine the work is advanced by means of a feed roll 48 coacting with the cement-applying roll 44 to grip the work therebetween, and the wiper disk or straightening tool 10 is rotated in the direction indicated by the 20 arrow, the work moving away from the operator. When a thickened portion of the work is encountered, such as shown in Fig. 4, the condition illustrated in that figure will obtain and the convolutions of the helical spring 32 will be displaced and slide axially along the ring 34 or 25 around the periphery of the tool in spite of the corrugations 39, thus relieving the action of the tool upon the work and avoiding scuffing or damage thereto.

Having thus described my invention, what I claim as new and desire to secure by Letters Patent of the United States is:

1. In a machine for straightening French binding, a driven wiping tool having a corrugated periphery, and a helical spring wrapped around said periphery and resiliently held in contact with the corrugations, said spring being normally held in position with respect to the periphery by the corrugations and allowed to slip with respect 35 to the periphery when an obstruction is encountered to prevent injury to a binding strip.

2. In a machine for straightening French binding, a driven disk having a grooved periphery, a rubbing work-contacting member comprising a 40 helical spring located in the groove and adapted

to yield along the axis of the spring, and a resilient split ring threaded through and substantially filling the coils of said spring to retain the spring in the groove while permitting circumferential displacement thereof along the ring when 5 extraordinarily resisted by a piece of work.

3. In a machine for straightening French binding, a driven wiper disk having a grooved periphery, transverse grooves formed in the bottom of the groove of said disk which are inclined with 10 respect to the plane of rotation of said disk, and a work-rubbing member comprising a helical spring located in the groove of the disk with its convolutions seated in the transverse grooves, said spring being resiliently held on said disk and 15 normally resting in said transverse grooves but adapted to slip around the periphery when an obstruction is encountered in a binding strip.

4. In a machine for straightening French binding, a rotary tool having a peripheral groove substantially U-shaped in cross-section, the bottom of said groove having corrugations and the sides of the groove being smooth, and a work-rubbing member resiliently held in the groove comprising a helical spring positioned in contact with said 20 corrugations and projecting slightly beyond the top of the groove to wipe across a binding strip. 25

5. In a machine for straightening French binding work having a binding strip attached to the edge of the work, cooperating rolls for feeding a 30 piece of work in the general direction of the edge of the work, one of said rolls being arranged for the application of cement to the work, a wiping tool comprising a carrier having a corrugated periphery and a helical spring wrapped around the periphery of the carrier and resiliently held 35 against the corrugations while allowed to slip circumferentially of the carrier, and means for rotating said wiping tool transversely of the direction of feed of the work to drag the convolutions of the spring across the outturned binding strip 40 approximately at the point of attachment to the work.

ARTHUR S. JOHNSON. 45
